CIRCULAR FIREPLACE

Glen D. Crownover, 3709 Douglas Drive,
Santa Rosa, Calif.

Filed May 25, 1961, Ser. No. 65,346

Term of patent 14 years

(Cl. D81—7)

The FIGURE is a perspective view of a circular fireplace showing my new design.

The other side of the circular fireplace is identical to the side shown with the exception that there is no access opening.

I claim:

The ornamental design for a circular fireplace, substantially as shown and described.
